UNITED STATES PATENT OFFICE.

EMIL L. PFUNDER AND FRANK A. COOK, OF HARTFORD, CONNECTICUT, ASSIGNORS TO UNDERWOOD TYPEWRITER COMPANY, OF NEW YORK, N. Y.

TYPE-WRITING MACHINE.

No. 853,562.

Specification of Letters Patent.

Patented May 14, 1907.

Application filed February 18, 1907. Serial No. 358,025.

To all whom it may concern:

Be it known that we, EMIL L. PFUNDER and FRANK A. COOK, citizens of the United States of America, residing at Hartford, in the county of Hartford and State of Connecticut, have invented certain new and useful Improvements in Type-Writing Machines, of which the following is a specification.

This invention relates to the mechanisms of type-writing machines which regulate the width of the side margin on the page of writing; and it is especially adapted to machines of the well known "Underwood" type, in which margin regulating devices are placed upon the front part of the machine convenient to the operator. In said machines, the mechanism for ringing a bell and locking the keys at the end of the line comprises a slide adjustable along a bar or rod on the frame and in front of the carriage; but the range of such adjustment was limited owing to the peculiarities of construction of certain portions of the margin-regulating mechanism. The means for stopping the carriage when returning to begin a new line included another slide mounted partly upon said rod and partly upon the carriage rail; but the adjustment of the last-mentioned slide was limited by reason of the presence of the line-locking mechanism already referred to.

One of the main objects of the present invention is to provide for greatly increased range of adjustment of both margin regulators; and to secure this result, both slides are made adjustable for a distance equal to nearly the entire length of travel of the carriage. Upon the rod already referred to, teeth are cut, to be engaged by a pawl provided upon the slide which regulates the end-of-the-line mechanism; while upon said carriage-rail are cut teeth engaged by the slide which regulates the limit of the return movement of the carriage to begin a new line; the latter teeth being formed upon said rail for nearly its entire length; the slide having a pawl to engage said teeth; and preferably each of the slides is mounted partly upon said rod and partly upon the rail. Said rod is in front of said rail and is preferably cylindrical, and mounted thereon is an arm extending backwardly and having at its free end a cam-device to be engaged by a corresponding cam-projection usually provided upon the carriage. The carriage is thus en-

abled to operate said arm, and the latter in turn has a projection to engage a bail which extends the entire length of said cylindrical rod or shaft, and is preferably hinged upon the latter in such manner that sufficient clearance is provided to permit said slides to move freely between the ends of said bail. Extending downwardly from said bail is an arm, which, at the rocking of the bail, rings a bell and locks the keys against depression in the same manner as is usual upon said Underwood machine. Said bail is engageable by said arm at any point to which the arm and its slide may be adjusted along the front of the carriage. Thus both slides or margin gage regulators may be placed either far apart or near together at either extreme of the carriage travel, thereby rendering it practicable to secure any width of margin on either the right or the left hand side of the written sheet, and it will be understood that said features of the invention may be employed in connection with constructions of margin-regulating mechanism other than those specifically shown and described herein.

In the accompanying drawings, Figure 1 is a front perspective view of a portion of an "Underwood" typewriting machine, embodying the present improvements; the parts being shown in position to lock the keys against depression. Fig. 2 is a perspective view similar to Fig. 1 but showing the keys released for further depression. Fig. 3 is a similar view but showing the key releasing mechanism in a different position, slightly retracted from that shown in Fig. 2, and returning to normal position. Fig. 4 is a similar view showing the parts in normal positions. Fig. 5 is a sectional elevation showing the line-locking slide, the parts being in normal positions. Fig. 6 is a plan of the parts seen at Fig. 5. Fig. 7 is a plan of the pawl; Fig. 8 is a plan of the cam-arm; and Fig. 9 a plan of the slide, seen at Figs. 5 and 6.

1 indicates the framework of the typewriting machine, and 2 the carriage, which is connected by a strap 3 to a spring barrel 4 and is provided with a front roll 5 to run upon a rail 6, preferably cylindrical. Mounted partly upon said rail and partly upon a parallel rod 7 in front thereof, is a slide 8 having a stop 9 to engage a releasable stop 10 formed upon an arm 11 pivoted at 12 upon the carriage and having a release key 13. A pawl

14 provided with a handle 15 and pivoted at 16 upon said slide has teeth to engage a series of ratchet teeth 17 formed upon the front side of the carriage-rail 6 and which may extend the entire length thereof. By pressing the handle 15 toward the left, the pawl 14 is rotated away from the teeth or rack, thus releasing the slide 8, which may be slipped as far as desired toward the left along the bars 6, 7. A finger-piece 18 is also provided upon the slide, to be grasped simultaneously with the handle 15, when it is desired to release the pawl and adjust the slide toward the right. The slide 8 is of the usual construction and operation; but the teeth 17 on the rail 6 extend along the rail 6 a sufficient distance to permit an adjustment of the slide 8 for a distance equal to about the entire length of the run of the carriage. With the exception of the increase in the number of the rack teeth, the construction so far designated is usual on said machine. In said Underwood machines, a bell 19 is struck by a hammer 20 to warn the operator of the near completion of the line of writing; the hammer being pivoted at 21 and operated by a trip 22, which is pivoted at 23 upon a pendant swinging arm 24. When said arm swings forwardly from the Fig. 4 position to the Fig. 3 position, it rides upon a cam 25 formed upon the bell-hammer, depressing the cam and lifting the hammer, the latter falling when the trip 22 passes the cam 25. Upon the trip 22 is also carried a pin 26 to engage an arm 27 provided upon a rock shaft 28, said pin thereby turning said shaft, and the latter operating to lock the keys. This is done by means of a transverse rod 29 carried upon arms 30 upon the shaft 28 and movable forward thereby beneath hooks 31 projecting up from key-levers 32 which operate the type bars 33, (the latter striking rearwardly against the front side of a platen 34, Fig. 5). The locking of the keys is seen at Fig. 1. If it be desired to release the keys, to add a few more characters on the end of the line of writing, a button 35 is pressed rearwardly so that a cone-like cam 36 thereon may engage the yielding arm 24 and press the same toward the right, so that the pin 26 may slip past the arm 27 and release the latter, which is returned to normal position by a spring 37, thus releasing the keys. The line-locking devices just described are in common use on said machine. According to the present invention, said arm 24 forms one arm of the bail, which is hinged upon the ends of the rod or shaft 7, the other arm being designated as 38, and the transverse bar which connects said arms, as 39. The rod 7 is rigidly secured upon the framework by nuts 40, and the bail is loosely hinged thereon. The bar 39 stands sufficiently above the rod 7, to clear the slide 8, as well as the companion slide now to be described. The bar 39 can be swung back-

wardly by a projection 41 formed upon an arm 42, which is loosely mounted upon the bar 7, to slide therealong and to rock up and down; said arm being confined in a recess 43 formed in a slide 44, which is mounted upon the bar 7 and rail 6 in a manner similar to the mounting of the slide 8 thereon. Said arm 42 carries at its rear free end a (transverse) cam-device 45 engageable by the usual cam projections 46, 47 provided upon the front of the carriage 2. When the projection 46, during the letter-feeding movement of the carriage, rides upon the bevel 48 at the right hand end of the cam-device 45, said device 45 is depressed and the arm 42 rocked on the rod 7, and the projection 41 forces the bar 39 rearwardly to swing forwardly the arm 24 and cause the trip 22 to force down the cam 25 and lift the hammer 20; the movement of the arm 24 continuing until the hammer is released and the bell sounded. The further movement of the carriage brings the cam projections 46, 47 to the position shown in Fig. 1 and causes sufficient additional movement of the arms 42, bail 39 and pendent arm 24, to lock the keys through the instrumentality of shaft 28 and rod 29 in the manner already described. The member 41, 42 has a transverse cylindrical perforation (indicated by dotted lines at Fig. 8) to fit upon the rod 7, to permit the rocking of the said member.

Upon the slide 44 is pivoted at 49 a pawl 50, having teeth 51 to engage a series of rack teeth 52 cut upon the rear side of the rod 7, a spring 53 serving to hold the teeth 51 normally in engagement with the rack. A handle 54 upon the pawl serves to release the pawl from the rack, so that by pressing said handle to the left, the slide 44 may be slipped along to the desired point upon the machine. The slide may be moved freely to the right by pressing upon a finger-piece 55 projecting forwardly from the slide, the pawl 51 riding idly over the rack 52. A tooth or hook 56 is formed upon the slide 44 to engage the projection 46 upon the carriage to arrest the latter at the point in its travel where the slide 44 may have been set to effect stoppage of the carriage; and to return the bail 39 and arm 24 to normal position after actuation, a spring 57 is provided which engages a crank arm 58 connected with said bail.

During the letter-feeding movement of the carriage to the left, the tappet 46 first strikes the incline 48 and depresses the arm 42 to ring the bell just before the Fig. 3 position is reached. When the carriage has proceeded a few more letter-spaces (each equal to the distance between each tooth and the next on rack 6 or 7), the tappet 46 strikes the higher cam 48^a, thereby depressing the arm 42 still more, and rocking the shaft 28 to lock the keys, as at Fig. 1; the projection 47 in the mean time having served to prevent arm 42

and arm 24 from returning to normal positions. Thereupon the button 35 is pushed back, releasing the keys, and then as the keys are struck one after another, the space 5 between tappets 46 and 47 comes to a point above the cam 48^a, whereby the latter and the arm 42 are permitted to rise, and the arm 24 may swing backwardly to enable the pin 26 to catch behind the crank-arm 27. Subsequently the tappet 47 rides upon the cam 48^a and re-locks the keys at the same time that the carriage becomes locked by the engagement of the side of the tappet-arm 46^a with the stop 56. The improvements may be used in connection with the structures shown in U. S. Patents 633,672 and 775,331.

The disclosure here made is merely illustrative, and it is obvious that variations may be resorted to within the scope of the invention, and that portions of our improvements may be used without others; and we do not limit ourselves to any of the details shown and described.

Having thus described our invention, we 25 claim:

1. In a typewriting machine and in combination, a carriage, a supporting rail therefor, a rod parallel with said rail, a slide mounted upon said rod and rail, means for locking said slide to said rail, a second slide mounted upon said rod and rail, means for locking said second slide to said rod, means controlled by one of said slides for arresting the movement of the carriage at the margin 35 on one side, and means controlled by the other of said slides for sounding the alarm and locking the carriage at the margin on the other side.

2. In a typewriting machine and in combination, a carriage, margin-regulating mechanism comprising a slide support, a slide movable on said support, means for locking said slide to said support, a rocking bar carried by said support, a member on 45 said slide operable by said carriage to oscillate said rocking bar, and margin-controlling devices in operative relation to said bar.

3. In a typewriting machine having a carriage and a rail therefor, the combination of a 50 rod or shaft parallel with said rail, a slide mounted upon said rod and rail and having a pawl, to engage teeth formed upon the rail, a second slide mounted upon said rod and rail and having a pawl to engage teeth formed upon the rod, means controlled by one of 55 said slides for arresting the return movement of the carriage to begin a new line and means controlled by the other of said slides for ringing a bell and locking the line.

4. In a typewriting machine having a carriage, the combination of parallel racks, the teeth on one rack directed opposite from those on the other rack, slides mounted upon 60 said racks, one slide having a pawl to engage one rack and the other slide having a pawl to

engage the other rack, devices controlled by one slide for regulating one side margin, and devices controlled by the other slide for regulating the other side margin on the written page.

5. In a typewriting machine having a carriage, the combination of parallel racks, the teeth on one rack directed opposite from those on the other rack, slides mounted upon said racks, one slide having a pawl to engage 70 one rack, and the other slide having a pawl to engage the other rack, a rocker bar extending along one of said racks and clearing said slides, end-of-the-line devices operable by said rocker-bar, and means upon one of said slides movable by the carriage for operating said rocker bar.

6. In a typewriting machine having a carriage, a margin regulating mechanism comprising a 75 rack, a slide movable along said rack and having a pawl to engage the same, a movable bar extending along the rack, a part upon the slide operable by the carriage to actuate said bar and margin-controlling devices operated by said bar.

7. In a typewriting machine having a carriage, the combination of a rack, a slide adjustable along said rack and having a tooth to engage the rack, a pivot-arm moving with said slide and operable by a part upon the 95 carriage, a bar extending along said rack moved by said arm, and margin-controlling devices operated by said bar.

8. In a typewriting machine having a carriage, the combination of a rod having teeth formed thereon, a slide mounted upon said rod and having a pawl to engage said teeth, an arm pivoted upon said rod and moving with said slide, a cam device upon the free end of said arm to be engaged by the carriage to rock the arm, a bail hinged upon the ends of said rod engaged by said arm, and bell-ringing and line-locking devices operated by said bail.

9. In a typewriting machine having a carriage, the combination of a rod or bar extending along the carriage, a bail hinged upon the ends of said rod or bar, slides mounted upon said rod or bar between the ends of said bail, means upon one slide operable by the carriage to actuate said bail, margin-regulating devices controlled by said bail, and a margin-regulating device controlled by the other slide.

10. In a typewriting machine having a carriage, the combination of a rod or bar extending along the carriage, a bail hinged upon the ends of said rod or bar, a slide mounted upon said rod or bar between the ends of said bail, means upon the slide operable by the carriage to actuate said bail, and margin-regulating devices controlled by said bail.

11. In a typewriting machine having a power-driven carriage provided with a front 130

roll and a rail upon which said roll runs, the combination of a rod parallel therewith, a margin-stop slide mounted upon said rail and rod and having a stop to engage a stop which is provided upon said carriage and also having a pawl to engage a series of ratchet teeth upon the front side of said rail, said series extending nearly the entire length of the rail, a second slide mounted upon said rail and rod, a pawl upon said second slide provided with a handle and having a tooth to engage a series of ratchet teeth formed on the rear side of said rod and directed oppositely from the teeth upon said rail, an arm journaled upon said rod and confined in a recess in said second slide, a bail journaled loosely upon the ends of said shaft and extending along the latter and engaged by a projection upon said arm, bell-ringing and line-locking mechanism operated by said bail, and a cam device upon the free end of said arm to be engaged by a part upon the carriage to rock said bail.

12. In a typewriting machine having a carriage, the combination of a rod, a slide mounted upon said rod, a pawl upon said slide provided with a handle and having a tooth to engage a series of teeth formed on said rod, an arm journaled upon said rod and confined by said slide, a bail journaled loosely upon the ends of said rod and extending along the latter and engaged by a projection upon said arm, bell-ringing and line-locking mechanism operated by said bail, and a cam device upon the free end of said arm to be engaged by a part upon the carriage to rock said bail.

13. In a typewriting machine having a power driven carriage provided with a front roll and a rail upon which said roll runs, the combination of a rod parallel therewith, slide mounted upon said rail and rod and having a stop to engage a stop which is provided upon said carriage and also having a pawl to engage a series of ratchet teeth upon said rail, a

second slide mounted upon said rail and rod, a pawl upon said second slide with a handle and having a tooth to engage a series of ratchet teeth formed on said rod and directed oppositely from the teeth upon said rail and bell-ringing and line-locking mechanism controlled by said second slide.

14. In a typewriting machine having a power-driven carriage provided with a front roll and a rail upon which said roll runs, the rail being supported by its ends upon the framework, the combination of a rod in front of said rail and parallel therewith, a margin-stop slide mounted upon said rail and rod and having a stop to engage a stop which is provided upon said carriage and also having a pawl to engage a series of ratchet teeth upon the front side of said rail, said series extending nearly the entire length of the rail, a second slide mounted upon said rail and rod, a pawl upon said second slide provided with a handle and having a tooth to engage a series of ratchet teeth formed on the rear side of said rod and directed oppositely from the teeth upon said rail, a spring for the last-mentioned pawl, an arm journaled upon said rod and confined in a recess in said second slide, a bail journaled loosely upon the ends of said shaft and extending along the latter and engaged by a projection upon said arm, bell-ringing and line-locking mechanism operated by said bail, a returning spring for said bail, and a cam device upon the free end of said arm to be engaged by a part upon the carriage to rock said bail to ring a bell and lock the keys; the second slide having fixed thereon a stop to engage said projection on the carriage to arrest the letter-feeding movement of the latter.
